UNITED STATES PATENT OFFICE.

CHARLES A. ERICKSON, OF LAKewood, OHIO.

AUTOMOTIVE RADIATOR CORE.

Application filed May 19, 1921. Serial No. 470,965.

The invention relates to improvements in the construction of units which enter into the manufacture of radiators of the type usually used in connection with the power plants of automobiles and the invention constitutes an improvement over a similar form of radiator unit disclosed in my copending application, Serial No. 366,975, filed March 18, 1920.

The device herein featured has for its general object the providing of a simple form of radiating unit the parts of which can be readily and easily formed and which at the same time provides for an arrangement whereby the water sections may be secured in separated position by combined radiating and spacing members designed to be installed in position between the water units without fastening means and without any necessity for a refinement of manufacture to insure accuracy of fit.

In the application above identified the spacing member is in the form of a corrugated strip positioned at opposite ends of each of the units and each strip having oppositely extending fins or projections for engaging in grooves in the contiguous face of the opposing water cells. This forms a double row of air pockets between each water section and under some circumstances this provides an unnecessary amount of radiating surface.

The invention herein disclosed features a spacing member in which the extensions are confined to one side of a corrugated end plate which has a fit against one side of the water cell and thus locates the extension in grooves formed solely in one of the opposing water cells.

Various other objects and advantages of the invention will be in part obvious from an inspection of the accompanying drawings and in part will be more fully set forth in the following particular description of one form of mechanism embodying my invention, and the invention also consists in certain new and novel features of construction and combination of parts hereinafter set forth and claimed.

In the accompanying drawings:

Figure 1 is a view in front elevation of a conventional form of radiator with a portion of the casing broken away to show in front elevation a preferred embodiment of the invention;

Figure 2 is an enlarged fragmentary view of the showing in Figure 1;

Figure 3 is a view similar to Figure 2 with the several parts in spaced relation to more clearly show the assemblage of units 60 of Figure 2;

Figure 4 is a view in side elevation of the part shown in Figure 2 and broken away centrally so as to minimize the width of the showing; and

Figure 5 is a composite view, the central portion of which is taken on the line 5-5 of Figure 2 and the end portions of which show adjacent parts in spaced apart relation.

In the following description and in the claims, parts will be identified by specific names for convenience of expression but they are intended to be as generic in their application to similar parts as the art will 70 permit.

The conduits of the radiator through which the water passes comprise passageways formed of water cells 10 which are of the conventional corrugated form and each of which includes side outlining walls 11 and 12 brought together at opposite edges 13 to form flat seams 14 enclosing the water space 15. The opposite walls of the adjacent water cells are maintained in spaced apart position by a pair of radiating members 16 and 17 disposed at opposite edges of the unit. These members are similar in construction so that a detailed description of either one will be sufficient for the other. 90 The spacing member is formed of a single strip of metal relatively narrow compared to the width of the water cell and of thin gauge sheet metal. The strip is formed into the cellular member disclosed by bending 95 spaced apart portions back upon itself to form outstanding flanges 18, which flanges are connected at adjacent ends by inclined single ply connecting portions 19 arranged to form air passages 20 between the same 100 and the adjacent side of one of the walls 11 or 12. From this construction it will be understood that the single ply connecting portions 19 coact to form a corrugated end wall which has the double ply extensions 105 projecting therefrom in the same direction as more particularly shown in Figure 3.

The end wall is caused to fit snugly against one side 21 of the two-ply seam 14 which side will be identified hereinafter as the 110

broader side of the seam for it will be noted from the showing in Figure 5 that one side of the seam is of greater width than the opposite side 22. The side 22 is designed to have the free ends of the projections in sliding engagement therewith and the portion of the side at the apex of the narrow side of the seam is provided with grooves 23 into which fit the inner portions of the projections as shown more clearly in Figure 5.

It will be understood that the water cells are preformed and that they are arranged in spaced apart position with the groove containing side of one cell oppositely disposed to the broader side seam of the other section and that the spacing and radiating units are slipped into place with the end wall engaging snugly against the corrugated broad face and thus positioning the extensions into the grooves facing the same. The parts will maintain this position without the necessity of securing the elements in place.

It is understood that the construction herein featured permits the use of a greater number of water cells than is possible with the showing in the above identified application and as the water cells can thus be made smaller there is a material increase in the amount of radiating surface compared to the amount of material used in the two constructions. As there is a necessity for interfitting only one set of extensions into the groove, the possibility of fit is enhanced and in general there is provided a mutually braced structural part of high heat radiating capacity.

While I have shown and described and

have pointed out in the annexed claims, certain novel features of my invention, it will be understood that various omissions, substitutions and changes in the form and details of the device illustrated and in its operation, may be made by those skilled in the art without departing from the spirit of the invention.

Having thus described my invention, I claim:

1. A radiator unit comprising two spaced apart water cells of zigzag configuration including side outlining walls brought together at opposite edges to form flat seams, arranged so that the contiguous walls of the cells form opposite sides of a series of cooling chambers and a bent metal strip arranged in intimate contact throughout its entire length with the inner face of one of said cells and having folded extensions all projecting in the same direction from said wall and engaging at their outer ends the respective apices of the other contiguous cell wall forming partitions for said chamber.

2. A radiator unit comprising in combination a pair of spaced water cells of zigzag configuration and a strip arranged in intimate contact throughout its entire length with the face of one of said cells contiguous to the other cell and having a plurality of folded extensions all projecting in the same direction into contact with the apex of the other cell wall.

Signed at New York city in the county of New York, and State of New York April A. D. 1921.

CHARLES A. ERICKSON.
